UNITED STATES PATENT OFFICE.

JOSEPH C. CRAMP, OF PHILADELPHIA, PENNSYLVANIA, ASSIGNOR OF ONE-HALF TO
HIBBERT S. HOLBY, OF PHILADELPHIA, PENNSYLVANIA.

BAG-CLEANER.

1,163,131.

Specification of Letters Patent.

Patented Dec. 7, 1915.

Application filed February 21, 1914. Serial No. 820,235.

To all whom it may concern:

Be it known that I, JOSEPH C. CRAMP, a citizen of the United States, residing at Philadelphia, in the county of Philadelphia and State of Pennsylvania, have invented certain new and useful Improvements in Bag-Cleaners, of which the following is a specification.

My present invention relates to improvements in devices which have for their especial object a full and complete emptying, or discharge of material of a pulverulent or pulverized nature, from the bags wherein such material is packed, and to the accomplishment of the purpose named, the said invention contemplates the provision of simple, durable and easily operated means, whereby a bag, after the material packed therein, has been emptied therefrom in the ordinary manner, may be subjected to a shaking movement in opposite directions, whereby such of the material as has found lodgment upon the surface, or in the body of said bag, may be dislodged or shaken therefrom and caused to fall into receptacles placed to receive the same, and to the end noted the invention consists in peculiar means and mechanism whereby a bag, when emptied of material and mounted upon a movable support within a suitable inclosing casing, is subjected to a sudden and sharp movement in opposite directions substantially in the manner hereinafter described, and illustrated in the accompanying drawings whereby such material as has found lodgment upon said bag, is dislodged therefrom.

Of the drawings referred to: Figure 1, illustrates in side elevation, the device as it appears when ready to be actuated for the purpose named. Fig. 2, is a vertical longitudinal section, taken through the actuating shaft, its inclosing casing and the parts thereto connected, to clearly illustrate the construction of the same. Fig. 3, is a transverse sectional view taken on the line x, x , of Fig. 1, looking downward toward the base of the device. Fig. 4, is a similar transverse sectional view taken on the line y, y , of Fig. 1, and looking downward toward the base of the device. Fig. 5, is an enlarged sectional detail view taken on the line z, z , of Fig. 1, through the tubular casing of the actuating shaft and the shaft actuating device, to show the connection of

the latter named with said shaft. Fig. 6, is an enlarged detail view, partly in section, of a portion of the actuating shaft, its tubular casing and the device by which said shaft is actuated. Figs. 7 and 8, illustrate modifications of the means for returning the actuating lever, or treadle to starting position. Fig. 9, illustrates, in elevation, a portion of the lower end of the actuating shaft, showing thereon modified means for rotating said shaft. Fig. 10, shows in plan view, the device which co-acts with the shaft shown in Fig. 9, to rotate the same.

It is a fact well known to those whose business or occupation necessitates the handling, or employment and use of pulverized material, such for instance, as hydraulic lime, or cement, that a very considerable loss occurs from and is consequent upon the lodgment of the dust like particles, of which such pulverized material consists, upon the surface or in the body itself of the container in which such material is packed. The fact above set forth, is particularly true when the bag wherein the material is packed, is made of burlap, or of material analogous thereto, because of the fact that the surface of such material is rough and coarse, and therefore peculiarly adapted to receive and to retain the dust like particles of such pulverized material.

In view of the foregoing recited facts the present invention has been made, its purpose being, to dislodge such pulverized material as remains upon the surface, or in the weave of the fabric of which the bag is made, after such bag has been emptied in the ordinary manner, by imparting thereto sharp and sudden jars, or shakings in opposite directions through the medium of simple and easily actuated devices, thus saving for use, material that otherwise would be lost.

Referring to the drawings which form a part of this specification, wherein one adaptation of my invention is shown and in the several views of which similar letters and numerals of reference denote like parts, 1, designates a base plate which, although here shown as being of metal and in circular shape, may yet be made of any desired material, suitable for such purpose, and of any desired form and shape, and I provide said base plate at, or near its middle, with an aperture 2, screw threaded to receive the lower screw threaded end of a tube 3, which

extends thence, in upward direction, to the desired distance to support a shaft 4, which centrally disposed and extending within the tube 3, is provided at its lower end with a 5 pivot 5, that is journaled in a bearing block 6, secured within the lower end of the tube 3, as shown.

The opposite upper end of the shaft 4, extends through and lightly contacts with a 10 centrally apertured bearing block 7, which, secured to the upper end of the tube 3, forms a journal bearing for the shaft 4, as shown in Fig. 2.

I provide the upper end of the shaft 4, 15 above the tube 3, with a circular plate, or wheel 8, which rigidly secured to said shaft rotates therewith, as will be presently described, for a purpose to be hereinafter set forth. I also provide the shaft 4, at a pre- 20 determined distance above the base plate 1, with a bearing block 9, through which said shaft extends, and with which it lightly contacts for the purpose of preventing lateral deflection of said shaft when it is operated, 25 as will be presently described.

I provide that the shaft 4, shall, when in action, be rapidly rotated in opposite directions, to impart a shaking, or slatting movement to the bag which is to be carried upon 30 said shaft, as will presently be more fully explained, and to such end I provide the lower end of the shaft 4, with a groove 10, and extend said groove about the shaft in spiral direction to engage a pin 11, that 35 projects into said groove from a short block or nut 12, which apertured for the passage therethrough of said shaft 4, is adapted to slide freely up and down within the tubular casing 3, upon the shaft 4, therein contained.

40 I provide that the block or nut 12, shall be held from rotation within the casing 3, to which end I provide the tubular casing 3, upon its opposite sides and near its lower end with slots 13, through which the screw 45 threaded shanks of bolts 14, extend to and into the opposite sides of the sliding block or nut 12, see Fig. 5.

I arrange that the sliding block or nut 12, shall be moved up and down within the tubular casing 3, to rotate the shaft 4, and to 50 such end provide that the bolts 14, upon the opposite sides of the casing 3, shall respectively, extend through short slots 15, one of which is formed through each of the rearwardly extending arms 16, and 17, of a treadle 18, which, hinged at 19, to a standard 55 20, that projects upwardly from the base plate 1, is adapted to be moved in downward direction, by pressure, and to be returned to its normal elevated position by a spiral spring 21, which surrounds the lower portion of the shaft 4, and bears at its opposite ends respectively upon the base 1, and the lower side of the block or nut 12, 60 see Fig. 2.

By the foregoing described construction of the operative parts comprised in my invention, it will be readily understood that a bag, of textile fabric, will—when placed in position upon the circular plate, or wheel 70 8, as indicated in Fig. 2, by the numeral 22, and subjected to the back and forth shaking, or slatting due to the action of the shaft 4,—be thoroughly cleansed from such particles of pulverized material as may have remained upon its surface, or in its texture, after such bag had been discharged in the ordinary manner. For the purpose of saving the material so discharged from the bag, I provide that the operation of cleansing 80 the same, as above noted, shall be carried forward within a suitable inclosing casing, and that the material discharged from the bag, shall be caught in suitable receptacles 85 provided for such purpose.

To the ends last above named, I provide the device, at a suitable distance above the base plate 1, thereof, with an open ended cylindrical casing 23, which, arranged concentric with the tubular casing 3, of the shaft 4, is secured to the upper ends of supports 24, which extend from and are rigidly secured, at their lower ends to the base 1, see Figs. 1 and 3, to maintain the casing 23, in proper position noted.

I also arrange, immediately below and partially surrounding the casing 23, a receptacle 25, for the material that is discharged from the bag, so arranging said receptacle as regards the casing 23, that its circular inclosing wall 26, shall be concentric with said casing 23, while its bottom 27, preferably cone shaped shall project upwardly within the lower end of the casing 23, at a short distance therefrom, so that material falling upon said cone shaped bottom 27, from the bag, when the device is operated, shall pass upon such bottom 27, below the lower edge of the casing 23, to the receptacle 25, to be discharged therefrom through a spout 28, which extends from one side of said receptacle as shown.

The receptacle 25, is held in proper position, as regards the casing 23, by the supports 24, which sustain said casing 23, in position and to which said receptacle 25 is also connected.

I provide that the conical bottom 27, of the receptacle 25, shall at its middle snugly fit against the tubular casing 3, of the shaft 4.

I provide that the operation of cleansing the bags shall be confined within inclosing walls, to which end, I arrange a cylindrical casing 29, having its upper end closed and its lower end open, above and concentric with the casing 23, and in position to be drawn downward, over the bag when it is in position upon the circular support, or wheel 8, and into the said casing 23, until

its lower end shall rest upon the bottom 27, of the receptacle 25, as shown in Fig. 2, at which time the operation of cleansing the bag is to be performed, and after which 5 said casing 29, is to be raised, to permit the removal of the cleansed bag from the support 8, and the placing of another thereon, as well as to permit the material, shaken from said bag to slide down the cone shaped 10 bottom 27, of the receptacle 25, to the wall 26, thereof to be withdrawn therefrom.

It is to be noted that the exterior surface of the bag inclosing casing 29, is purposely proportioned to lightly contact with the internal surface of the casing 23, so that when 15 the device is in operation, the bag inclosing casing, is held in proper position, by said casing 23.

If desired the lower end of the shaft 4, 20 may be provided with a cone shaped recess 30, to bear and turn upon a cone shaped bearing 31, instead of having a journal bearing similar to that shown at 5, in Fig. 2, see Fig. 6.

25 If desired the treadle 18, may, when pressed downward by the foot of an operator, be returned to normal starting position by a counter weight 32, that is arranged upon an extension of said treadle, beyond 30 its fulcrum, as shown in Fig. 7, instead of being returned to normal starting position by a spiral spring 21, held within the casing 3, as shown in Figs. 1 and 2, or such treadle 18, may, at its rear end below its 35 pivotal point 19, be provided with a depending arm 33, to receive at its lower end, one end of a coiled spring 34, the opposite end of which, is connected to a support 35, as shown in Fig. 8, instead of the construction shown in Figs. 1 and 2.

In Fig. 9, I show a device which may be employed instead of the tool cut spiral groove 10, in the shaft 4, such device consisting of a flat piece of metal of proper size, so twisted upon itself that its side edges shall extend in spiral direction, as shown at 40 36, and provided at its lower end with a journal 37, to engage a bearing in the lower end of the tubular casing 3, and at its upper end, with a step 38, to enter a recess 39, in the lower end of the shaft 4, and having an actuating nut 40, peculiar to the twisted portion 36 of said shaft, in that said nut is formed by placing a section of tubing, of 45 proper length about the twisted section 36, and pouring heated Babbitt metal, or other suitable material, into the tube section, about such section 36, to form the actuating nut 40, shown in Fig. 10.

50 The operation of the device will, it is thought, be understood from the foregoing description, taken in connection with the accompanying drawings, it only being necessary to here state, that the bag to be acted upon, is placed in position upon the rotata-

ble disk, or wheel 8, as shown in Fig. 2, the inclosing casing 29, drawn down to cover said bag, as shown in Fig. 1, and the treadle 18, forced up and down any desired number of times, to accomplish the desired end. 70

While I have herein shown and described one adaptation of my invention, I yet do not wish to confine myself solely to such adaptation, as different adaptations of such invention may be made to accomplish the 75 same result, I therefore claim the right to make any and all such modifications of said invention, as shall fall within the scope and limit of the claims hereto appended.

Having thus described my invention, I 80 claim and desire to secure by Letters Patent—

1. In bag cleansing apparatus a supporting base, a shaft vertically mounted upon said base, a support upon said shaft to receive a bag, a lever operatively connected with the shaft and hinged to the base to be moved in one direction to turn the shaft and its supported bag a predetermined distance, and means operatively connected to the lever 85 to return said lever and its actuated shaft to normal starting position, substantially as described.

2. In bag cleansing apparatus a supporting base, a rotatable shaft mounted thereupon, a support upon said base to receive said shaft, a disk upon said shaft to support a bag, a lever operatively connected with the shaft and hinged to the base to be moved in one direction to turn the shaft and its supported bag a predetermined distance, operating connections between said lever and said shaft, and a spring connected to the lever to return said lever and its supported bag to normal starting position, substantially as described. 100

3. In bag cleansing apparatus a supporting base, a shaft vertically mounted upon said base to rotate thereon, a disk upon said shaft to support a bag, a lever operatively 105 connected with the shaft and hinged to the base to be moved by pressure in one direction to rotate said shaft and its supported bag a predetermined distance, means to return said lever and its connected shaft to 110 normal starting position, and a receptacle to receive material discharged from the bag carried upon said shaft, substantially as described.

4. In bag cleansing apparatus a base, a 115 rotatable shaft vertically mounted upon said base, a disk upon said shaft to support a bag, said shaft having a groove extending spirally thereabout, a slidable block mounted to move upon said shaft, a pin projecting 120 from said block to engage the groove in the shaft, means to hold the block from rotation, and means to move said block upward and downward to rotate the shaft and its supported bag, substantially as described. 130

5. In bag cleansing apparatus a base, a rotatable shaft mounted upon said base and provided with a disk to support a bag, a tubular casing extending from the base immediately about the shaft to support the same, said shaft having a groove formed therein and extending spirally thereabout from end to end thereof, a sliding block apertured to move upon the shaft within the 10 tubular casing and having a pin to engage the groove in said shaft, a lever hinged to the base to swing upward and downward, and connections between said lever and the sliding block to move said block when the 15 lever is actuated to move the shaft, substantially as described.

6. In bag cleansing apparatus a base, a casing supported thereabove, a rotatable shaft vertically supported within said casing and having a disk upon its top to support a bag and a groove formed therein and extending spirally thereabout, a tube extending vertically within the casing to support the rotatable shaft and having longitudinally extending slots formed therein, a block mounted upon the shaft to slide thereon and having a pin to engage the spiral groove formed in said shaft, a lever hinged to the base to swing up and down, and connections extending through the slots in the 30

shaft supporting tube to operatively connect the sliding block with the lever to move said block when the lever is moved up and down, substantially as described.

7. In bag cleansing apparatus a supporting base, a cylindrical receptacle supported at a distance above said base and provided with a cone shaped bottom and with a discharge spout, a cylindrical open ended casing 23 supported at a distance above the cone shaped bottom of the receptacle noted, and an inclosing casing movable within the casing 23 to contact with the cone shaped bottom of the cylindrical receptacle, in combination with a shaft vertically mounted upon the supporting base, a support upon said shaft to receive a bag, a lever operatively connected with the shaft and hinged to the base to be moved in one direction to turn the shaft and its supported bag a predetermined distance, and means operatively connected to said lever to return said lever and shaft to normal position, substantially as described.

In testimony whereof I hereto affix my 55 signature in presence of two witnesses.

JOSEPH C. CRAMP.
